UNITED STATES PATENT OFFICE

HERMAN J. S. LEWIS, OF NEW YORK, N. Y., ASSIGNOR OF ONE-HALF TO JOHN H. DALE, OF NEW YORK, N. Y.

STARTER FOR EXPLOSION-MOTORS.

No. 874,913.

Specification of Letters Patent.

Patented Dec. 24, 1907.

Application filed March 4, 1907. Serial No. 360,346.

To all whom it may concern:

Be it known that I, HERMAN J. S. LEWIS, a citizen of the United States, residing at the city of New York, in the county of New York and State of New York, have invented certain new and useful Improvements in Starters for Explosion-Motors, of which the following is a full, clear, and exact description.

10 My invention relates to a form of spring motor, particularly adapted for use in connection with explosion engines and motor vehicles, for the purpose of initially starting the engine from a state of rest.

15 In order to constitute a satisfactory starter for the engine of an automobile, or a similar installation, it is important that the application of the power be easily controlled whenever desired, and that this power be 20 obtained in an easy way, as, for example, from the engine at a time when it is running freely. In order to accomplish these purposes by a spring motor it is evident that a special construction is required in which the 25 power is stored and subsequently delivered from the rotary movement of the same shaft and in the same direction in both cases. In other words, the spring motor applied to the

30 crank shaft of the engine for initially rotating the same, must be capable of afterward having its power restored by the continuing rotation of this shaft in the same direction. Not only must these requisites be satisfied, but there is the further requirement that in 35 normal running the said shaft must be entirely free and disconnected from the mechanism of the spring motor. In carrying out the present invention I accomplish these purposes, and I have provided a simple

40 strong and compact mechanism which may be attached to the crank shaft of an explosion motor at any point, either in front of the radiator, or near the fly wheel in an automobile, or at any convenient location in 45 a launch, or other relation. All the functions of the spring motor are adapted to be controlled by the movement of a single part or lever, which may be extended to be operable from a point at the seat of the driver.

50 I consider this control by a single lever or part as a very important feature of the invention.

In the drawings: Figure 1 is a side eleva-

tion showing a spring motor embodying the principles of my invention; Fig. 2 is a longitudinal sectional view of the same; Fig. 3 is a sectional view on the line III—III of Fig. 2, looking in the direction of the arrows; Fig. 4 is a view of the interior of the casing, looking toward the left in Fig. 2; Fig. 5 is a view of the inside of the cover or plate on the right-hand side of the casing; Fig. 6 is a view of the casing with both end plates or covers removed; Figs. 7 and 8 are respectively side and sectional views of one of the cams; together with its operating lever; Fig. 9 is a detail perspective view showing a pawl or detent used in the construction.

Referring to the drawings in which like parts are designated by the same reference sign, 1 denotes the casing which is generally cylindrical in form, having a central peripheral wall 2, and end plates or covers 3 and 4, secured in any suitable way. Axially through this casing there is passed a shaft 5, 75 which is freely revoluble in the journal bearings 6 and 7 of the casing. On this shaft 5 there is keyed or splined a sleeve 8, so as to be capable of slight longitudinal movement on the shaft.

80 9 denotes a plate with a slightly coned edge forming part of the sleeve 8. There is also a second coned disk 10, which is splined on the sleeve 8, by means of the internal lugs 11, which enter the longitudinal slots or 85 grooves 12, of the sleeve. The coned disks 9 and 10 constitute clutch disks in combination with certain other parts of a spring drum, as will later appear.

I provide means loosely revoluble around 90 the shaft 5 for supporting a spiral spring. For this purpose there is shown a disk 13, having a central hub 14, which loosely surrounds the sleeve 8.

15 denotes the spiral spring which is 95 heavily made of spring steel so as to have the requisite power, and the inner end of this spring is fixed to the hub 14 of the disk 13.

16 denotes a second cup-shaped part or disk, having a hub 17, which also loosely surrounds the sleeve 8. The part 16 has a peripheral flange 18, to which the outer end of the spring 15 is fixed. In this way the disks or parts 13 and 16 are spring tensioned to take a predetermined angular relation with 100 15 one another, and are strongly impelled to re-

turn to such relation whenever displaced from it. They are both capable, however, of freely revolving about the shaft 5, unless held thereto in a special way. These characteristics are the important ones in connection with the main spring and its supporting parts, and it is evident that the details of construction by which they are obtained may be modified. In the drawing the spring 15 5 is fixed to the hub 14 by the expedient of having an intermediate collar or ring 19, which is keyed at 20, to the disk 13 so as to be removable therefrom. This construction is merely a convenient one in practice and 10 enables the parts to be readily taken apart and reassembled.

There is fixed to each of the disks or parts 13 and 16, a means coöperating with the clutch disks 9 and 10, by which said parts 20 are selectively engaged thereto. This is conveniently secured by internally coned rims 21 and 22, for the respective parts 13 and 16. These internally coned rims surround the clutch disks 9 and 10, as clearly shown in 25 Fig. 2. These rims also serve an additional function as thrust bearings to keep the main spring in its proper central relation in the casing. The casing has internally projecting lugs 23 and 24, which abut against the 30 rims 21 and 22, so as to limit the endwise movement. The clutch disks 9 and 10 are, therefore, engaged upon the parts 13 and 16 respectively when said clutch disks are moved in the proper longitudinal direction 35 on their supporting shaft. I provide means controlled by a single lever or part for engaging either of the clutch disks 9 and 10 in this way, or disengaging them both simultaneously. There are a pair of arms 25 and 40 26 loose on extensions of the sleeve 8, and these arms have central hubs or pieces 25' and 26', which abut against the clutch disks 9 and 10 respectively. The outer faces of the hubs 25' and 26' have cam inclines 25" 45 and 26". The journals 6 and 7 have corresponding cam inclines 27, 28 (see Figs. 4 and 5 respectively). The relation of the cam inclines is such that when the levers 25 and 26 are moved, one or another of the clutch 50 disks is engaged with the parts 13 and 16, depending on the direction of movement of said levers. When the levers are in the central position shown, both of the clutch disks are disengaged from the parts 13, 16. In 55 order that the levers 25 and 26 may project past the rims 23 and 24, the latter are interrupted for a portion of their circumference, as shown in Figs. 4 and 5. The outer ends of the levers 25 and 26 are deflected or bent 60 toward one another, and notched at 29 and 30 respectively. 31 denotes a block entering both such notches, and which is attached to a handle 32 circumferentially movable on the casing 1 by reason of a guiding slot 33

therein. When the handle 32 is swung back 65 and forth, the levers 25 and 26 are correspondingly moved and one or another of the clutch disks 9 and 10 is cammed inward, depending on the direction of movement of said handle 32. 70

The disks or parts 13 and 16 have ratchet teeth 34 and 35, on their outer edges, which point in opposite directions. The direction of the teeth 34 is clearly shown in Fig. 3; the direction of the teeth 35 is opposite thereto, 75 and shown at the lower part of this figure. The cover or plate 3 of the casing has a pawl 36, pivoted thereto at the point 37. 38 denotes a tail or extension of this pawl by 80 which it is moved out of engagement with the ratchet teeth 34 against the tension of a spring 39. The tail or extension 38 of the pawl is in the path of movement of the lever 25, so that the pawl is thrown out of engagement with the ratchet teeth at the limit of 85 movement of such lever. The other ratchet wheel 35 is constantly engaged by a spring or pawl 40, so as to prevent any return movement thereof under all circumstances and 90 conditions.

It has been stated that the pawl 38 is disengaged at the limit of movement of the lever 25, which has the function at the same time of camming the clutch disk 9 into its engaging relation. In order that the two 95 functions may be properly attained without interfering with one another, it is best in practice to have the cam inclines 25" slightly flattened at their highest points, as shown at 41, and the cam inclines 27 of the 100 journal 6 similarly flattened at 42. In this way the lever is free to move to its extreme position after the clutch disk has been fully tightened. An additional feature of the invention lies in having the journals 6 and 7 105 adjustable inwardly with respect to the end plates or covers of the casing by means of the screws 43. In this way the parts may be initially positioned to give the best results and adjustment thereafter made from time 110 to time as required to compensate for wear.

The operation is as follows: I will imagine the spring motor to be placed on the crank shaft 5 of an engine. The engine being initially started in the first instance in any 115 suitable way, the spring motor is tensioned by moving the handle 32 in the direction of the arrow 44 in Fig. 3. The effect of moving the handle 32 in this way is to tighten the clutch disk 10 upon the internally coned rim 22, and when this engagement is made the disk or part 16 revolves with the shaft 5. The power is therefore transmitted from the shaft through the sleeve 8 and clutch disk 10 and part 16 to the main spring 15 which is 120 thereby wound up. After a time, and when the main spring has been considerably wound, so that the engine begins to slow

down, or the clutch to slip, the handle 32 is moved back to its central position, disengaging clutch disk 10 and again allowing the crank shaft to revolve freely. The power stored up is, however, retained because the pawl 40 engages the teeth 35 of the disk or part 16, and prevents retrograde movement. In the meantime the disk or part 13 has been held against the tensioning of the spring by the pawl 36. The power is thus stored up for use and the engine may thereafter run freely as long as is required. When on a later occasion it becomes necessary to again start the engine, the handle 32 is moved toward the left or in the direction of the arrow 45, in Fig. 3, so that the clutch disk 9 is engaged with the internally coned rim 21. By the time the handle 32 has reached the limit of its movement, the clutch parts are very tightly engaged so that when the lever strikes the tail 38 of the pawl 36 to release the same, the power of the main spring is transmitted through the disk 9 to the shaft 5. Since the disk 13 in its unwinding movement naturally tends to follow the direction of the disk 16 in the winding movement, it is evident that the shaft 5 will be propelled in the same direction as it ran when the power was being stored up. The engine is therefore given the few initial rotations necessary to start it.

A very important feature of the invention lies in the fact that my starting mechanism does not require immediate and skilled attention to disconnect it from the crank shaft after it has given the few initial rotations required. Explosion engines start very suddenly, and the operator is occupied with the throttle and spark levers so that he would not have much opportunity to give any attention to the spring motor. But although the handle 32 is not returned immediately to its central position, there is no harm done, because after the energy of the spring is expended, all the parts, including the clutch disks, the spring and the parts 13 and 16, rotate together within the casing as long as desired, such motion in such forward direction not being resisted by the permanently engaged pawl 40. The operator of the machine can move the handle 32 to its central position or to the rewinding position at any time at his convenience. The rewinding is preferably done when the load of the machine is taken off the engine. It is evident that in going down hill, the greatest power is available, as the weight and momentum of the car may be used to assist the engine in obtaining the requisite power for a very stiff main spring.

A still further feature of the invention lies in the manner in which the disengagement of the clutch disks 9 and 10 is insured. Since these clutch disks should never be engaged

at the same time, I make the slots 12 just deep enough so that the lugs 11 will shoulder against their bottom faces when the two clutch disks are slightly disengaged from the two coned rims. In this way the clutch disk 10 is positively pushed into an extreme disengaged position whenever the clutch disk 9 is engaged, and conversely, the clutch disk 9 is pushed to an extreme disengaged position whenever the clutch disk 10 is engaged. In this way their action with the spring motor mechanism is made positive so that accidental binding or undue friction at any time will not destroy its effectiveness.

What I claim is:

1. A spring operated starter for explosion engines comprising two parts or members independently revoluble on the crank shaft of the engine, a power spring impelling said members angularly with respect to one another, and a lever pivoted coaxially with said members and movable in one direction to engage one member to the shaft and movable in the other direction to engage the other member to said shaft, said directions being in the plane of rotation of said shaft, and means for holding the non-engaged member stationary in each case. 80

2. A spring operated starter for explosion engines comprising two parts or members independently revoluble on the shaft to be actuated, a power spring impelling said members angularly with respect to one another, friction clutches for engaging either member with said shaft, means for holding the non-engaged member stationary, and means including cams angularly movable coaxially of said members for engaging either of said clutches selectively. 95

3. A spring operated starter for explosion engines comprising two parts or members independently revoluble on the shaft to be actuated, a power spring impelling said members angularly with respect to one another, clutches for engaging either of said members to the shaft, and a single part movable in the plane of rotation of the members for engaging either one of said clutches and simultaneously disengaging the other clutch. 105

4. A spring operated starter for explosion engines comprising two parts or members independently revoluble on the shaft to be actuated, a power spring impelling said members angularly with respect to one another, clutches for engaging either member to said shaft, a pair of levers abutting against said clutches, said levers having cam inclines and stationary cam inclines cooperating therewith whereby the clutches are engaged when said levers are moved. 115

5. A spring operated starter for explosion engines comprising two parts or members independently revoluble on the shaft to be actuated, a power spring impelling said mem- 125

bers angularly with respect to one another, clutches for engaging either member to said shaft, a pair of levers abutting against said clutches, said levers having cam inclines and adjustable stationary cam inclines co-operating therewith whereby the clutches are engaged when said levers are moved.

In witness whereof, I subscribe my signature, in the presence of two witnesses.

HERMAN J. S. LEWIS.
